J. N. REYNOLDS.

CALL FINDER FOR AUTOMATIC AND SEMI-AUTOMATIC TELEPHONE SYSTEMS.
APPLICATION FILED DEC. 13, 1916.

1,270,326.

Patented June 25, 1918.

Inventor:
John Newberry Reynolds

by S. C. Hanes, Atty.

UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

CALL-FINDER FOR AUTOMATIC AND SEMI-AUTOMATIC TELEPHONE SYSTEMS.

1,270,326.

Specification of Letters Patent. Patented June 25, 1918.

Application filed December 13, 1916. Serial No. 136,644.

To all whom it may concern:

Be it known that I, JOHN NEWBERRY REYNOLDS, a citizen of the United States, residing at Greenwich, in the county of Fairfield and State of Connecticut, have invented certain new and useful Improvements in Call-Finders for Automatic and Semi-Automatic Telephone Systems, of which the following is a full, clear, concise, and exact description.

This invention relates to automatic and semi-automatic telephone systems.

In an application for patent filed in the name of Samuel B. Williams, Jr., Serial No. 15 858,461, filed August 25, 1914, for improvements in automatic telephone systems, assigned to the same assignee as the present application, a telephone system is described which is characterized by a distributor or 20 call finder common to a group of lines which successively tests said lines, and, when it finds a calling line which has not already been seized by a line finder, starts a line finder hunting for said calling line. In said 25 Williams application the call finder is described as being a constantly driven switch of the brush and commutator type.

The object of the present invention is to provide a new and improved call finder 30 adapted for use, for example, in a system such as that described in the aforesaid Williams application, although obviously a switch of this character may be used for other purposes. One of the advantages of 35 the device hereinafter described resides in the fact that the contact members are not of the brush and commutator type which is subject to excessive wear, but are of a type having much better wearing qualities.

40 The drawing is a perspective view, certain parts being broken away, of a call finder embodying the present invention, in connection with which certain apparatus and circuits are diagrammatically indicated.

45 At A is indicated in the usual conventional manner the substation apparatus of one of the group of telephone lines connected to the call finder hereinafter described. It is to be understood that the conductors 2 and 3 extending to said substation not only are connected to the call finder, but also extend to a plurality of line finders, one of which is illustrated diagrammatically at

B. These line finders are common to a group of substations of which the substation 55 A is one. It is also to be understood that the purpose of the call finder hereinafter described and the relays C and D coöperating therewith, is to complete the circuit of the starter wire 4, which causes one of a plurality of line finders, such as B, to operate and seize the calling line. The relay C of the present system has the same function as the relay 123 of said Williams system; and the starter wire 4 of the present system corresponds to the starter wire in the system of the aforesaid Williams application which extends from the fixed contact of the relay 123 to the winding of the relay 136. It is also to be understood that the resistance E 60 shown in the drawing of the present application corresponds to the resistance 121 of said Williams application; and that said resistance, as in the system of the Williams application, is common to the test circuit of 70 the call finder hereinafter described, and to a plurality of circuits completed in parallel from the battery whenever a line finder has seized the line leading to the substation A. 75

The structure of the call finder and the 80 manner in which it performs its function will now be described. The call finder consists of the stationary metal rings 5, 6 and 7, separated from each other and from the supporting members 8 by means of insulating rings 9, 10 and 11. To the outer ends of these members 8 is fixed a metal ring 12, supporting the radially disposed groups of springs 13 embedded in insulating material 14. The individual springs 15, 16 and 17 of 90 each group are of different lengths, and so arranged that when depressed, they make contact with rings 5, 6 and 7, respectively. Springs 16 and 17 are connected together by means of the insulating stud 18, and to 95 springs 17 is attached a pole piece 19 of magnetic material.

Centrally disposed in this structure is a shaft 20, to which is secured an arm 21, at the free end of which is attached electromagnet 100 22. The shaft 20 may be rotated through the gear wheel 24 by any well-known driving means (not shown). The electromagnet 22 is, by this means, passed underneath one pole piece 19 after the other, and will therefore, if energized, bring each pair of springs 105

16 and 17 in succession into contact with their respective rings 6 and 7. Each spring 17 is provided with a wedge 23, adapted to press in between the two rollers 25, mounted on electromagnet 22, so that each pair of springs can be brought down only when the magnet is exactly in line with the same. The constant movement of the electromagnet 22 will, by means of these rollers 25, positively drive one pair of springs away from contact with rings 6 and 7 before the next pair can be attracted. At the upper end of shaft 20 is rigidly secured an arm 26, in which is rotatably mounted a shaft 27 pointing in the same radial direction as and parallel with arm 21. On shaft 27 there is fixed a gear wheel 29, engaging a crown gear 31 mounted on top of ring 5. A star-wheel 30, also fixed on shaft 27, is adapted by means of its tips to successively engage and press springs 15 into engagement with the ring 5 when the shafts 20 and 27 are rotated. The springs 16 and 17 of each pair are connected to conductors, such as 2 and 3, leading to a subscriber's station, such as A, and all contact springs 15 are connected to a common conductor leading through a resistance E to ground. To the rings 6 and 7 are connected conductors leading to a relay C, and ring 5 is connected to a relay D which, by means of its armature 41 and through the medium of brushes 42 and contact rings 43, is adapted to close the energizing circuit 40 for the magnet 22.

35 The operation of the apparatus is as follows: When the subscriber at station A lifts his receiver from the hook and when the constantly rotating star-wheel 30 depresses the corresponding spring 15, a circuit is established from battery, through relay D, ring 5, spring 15, resistance E, to ground. This energizes relay D and closes at 41 the energizing circuit 40 for electromagnet 22, and the corresponding pair of springs 16 and 45 17 are thereby attracted by electromagnet 22, and contact is made with rings 6 and 7. A circuit is thereby established from battery, through left-hand winding of relay C, ring 7, spring 17, conductor 3, through subscriber's station A, conductor 2, spring 16, ring 6, right-hand winding of relay C, to ground. Relay C is now energized and at contacts 48 connects ground to conductor 4. All these three circuits are broken as soon 55 as the electromagnet 22 and star-wheel 30 pass to the next group of springs 13. The ground on conductor 4 may be utilized to start a line finder to hunt for the calling line terminals in a manner similar to that shown 60 in application of S. B. Williams, Jr., Serial No. 858,461, hereinbefore mentioned, in which the conductor leading to the relay 126 corresponds to the conductor 4 of this application. Whenever the star-wheel 30 depresses a spring 15 of a line that is busy,

that is, one that is already connected to a line finder, the relay D will not pull up, due to the fact that the resistance E is shunted by the make busy resistance 52 in the engaged line finder, the conductor 34 being connected in multiple to all line finders in the group. 70

What is claimed is:

1. The combination with telephone lines, of a call finder comprising a set of movable terminals for each line, stationary contacts each being common to one terminal in each set, mechanical actuating means for causing one terminal of each set to successively engage their common contact, electromagnetic 80 actuating means for causing the other terminals in each set to engage with their common contacts, and a relay controlled by a circuit through the first-mentioned terminals and contact for operating said electromagnetic means. 85

2. The combination with telephone lines of a call finder comprising a set of movable terminals for each line, stationary contacts, each being common to one terminal in each set, mechanical actuating means for causing the corresponding terminals in each set to successively engage their said common contact, electromagnetic actuating means for causing the other terminals in each set to engage their common contacts, and means for moving said mechanical and electrical actuating means in unison from set to set. 90 95

3. The combination with telephone lines of a call finder comprising a set of movable terminals for each line, stationary contacts, each common to one terminal in each set, a rotatable shaft, mechanical means operated by the rotation of said shaft for causing the engagement of a terminal in each set in succession with their common contact, and electromagnetic means associated with said shaft for causing the engagement of the other terminals in each set with the other common contacts respectively. 100 105 110

4. The combination with telephone lines, of a call finder comprising a set of movable terminals for each line, stationary contacts each common to a series of terminals in each set, mechanical means for causing the engagement of one terminal in any set to their common contact, a relay controlled through said terminals and their common contact, and an electromagnet controlled by said set for causing the engagement of the other terminals in any set with their common contacts, and means for moving said mechanical means and electromagnet from set to set. 115 120

5. The combination with telephone lines of a call finder comprising a movable test terminal for each line, movable line terminals for each line, corresponding stationary contacts common thereto, mechanical means for causing the test terminals to engage in succession with their common contact, test- 125 130

ing means successively controlled through said test terminals and their common contact, electromagnetic means controlled by said testing means for causing the corresponding line terminals to engage in succession with the other common contacts, and a circuit controlling means actuated by the

circuit through said line terminals and their common contacts.

In witness whereof, I hereunto subscribe my name this 11th day of December, A. D. 1916.

JOHN NEWBERRY REYNOLDS.
